6 Claims. (Cl. 135—3)

The present invention relates to tents in general, and more particularly to an improved skeleton structure for tents. Still more particularly, the invention relates to an improved connecting and tilting or flexing structure for the upper end portions of tent poles or ribs.

Camping tents and many other types of tents are normally provided with a skeleton structure or frame which comprises elastically deformable tent poles or ribs consisting of wood, metal or plastic. Depending on the shape of the tent, two or more arcuate or straight tent poles or ribs are assembled into a skeleton frame which may be deformed to thereby expand the canvas into the form of a dome, cupola or the like. The lower end portions of the poles are anchored adjacent to the lower edge of the canvas, and the upper end portions of the poles are bent pairwise toward each other prior to being coupled by means of bolts or similar detachable fasteners. Proper manipulation of such fasteners requires skill and consumes much time, especially when the tent is to be erected at a camping site or the like. Also, flexing of the upper end portions of tent poles requires considerable force. The situation is further aggravated when the skeleton structure comprises a large number of tent poles and when the poles are long.

Accordingly, it is an important object of the present invention to provide a very simple, readily collapsible and easy-to-manipulate skeleton structure for dome-shaped camping tents and the like, and to construct the skeleton structure in such a way that its tent poles or ribs may be flexed or tilted in a single operation.

Another object of the present invention is to provide a novel connection for the upper end portions of two or more tent poles.

A further object of the invention is to provide a connection wherein the manipulation of a single element suffices to effect flexing or tilting of tent poles for the purpose of erecting or collapsing a skeleton structure.

An additional object of the invention is to provide a connection which is capable of automatically flexing or tilting all of the tent poles to the same extent or which can selectively tilt one or more tent poles to a different extent than the remaining pole or poles.

Still another object of the present invention is to provide a skeleton structure of the above outlined characteristics wherein the flexing or unflexing of tent poles may be brought about by resorting to a very simple tool.

A concomitant object of the invention is to provide a tent which embodies a skeleton structure of the above outlined characteristics and wherein the connection between the upper end portions of assembled tent poles may be applied or removed either from below, i.e., from the interior of the tent, or from above, depending on the overall height of the skeleton structure and on the height of the person in charge.

Still another object of the invention is to provide a skeleton structure which may comprise straight or arcuate tent poles, which may comprise a total of two poles or three or more poles, and which is of the self-locking type so that the connection between the upper end portions of the tent poles cannot be terminated accidentally against the will of the occupants.

Another object of the invention is to provide a skeleton

2

structure which can be very rapidly assembled or taken apart, wherein the connection between the upper end portions of the tent poles is of very simple, inexpensive and compact design so that it occupies little room during transportation to a different camping site, wherein the tent poles may be assembled or detached independently of each other, and wherein the connection simultaneously assists in preventing water from entering through the apex of the fully assembled tent.

10 Briefly stated, one feature of my present invention resides in the provision of a skeleton structure which is particularly suited for use in dome-shaped tents with arcuate tent poles or ribs consisting of elastically deformable material. The skeleton structure comprises a plurality of tent poles the lower end portions of which may be secured in or to the ground at a camping site, hollow supporting means having a substantially vertical axis and including fulcrum means removably receiving the tent poles in such a way that the upper end portion of each pole extends into the interior of the supporting means, and tensioning means mounted on the supporting means and arranged to tilt the poles with reference to the fulcrum means. The tensioning means comprises motion transmitting means arranged to engage the upper end portions of the poles, and means for shifting the motion transmitting means in the axial direction of the supporting means whereby an intermediate portion of each pole is tilted with reference to the fulcrum means to thereby stretch the canvas when the motion transmitting means moves in one direction and to reduce the tension upon the canvas when the motion transmitting means is shifted in the other direction.

35 The novel features which are considered as characteristic of the invention are set forth in particular in the appended claims. The improved skeleton structure itself, however, both as to its construction and the mode of assembling and manipulating the same, together with additional features and advantages thereof, will be best understood upon perusal of the following detailed description of certain specific embodiments with reference to the accompanying drawings, in which:

40 FIG. 1 is a side elevational view of a connection for the upper end portions of tent poles, further showing one of the tent poles and a tool which is used to effect axial movements of the motion transmitting member with reference to the supporting means, certain parts of the connection being shown in section;

45 FIG. 2 is a similar side elevational view of the connection showing one of the tent poles in tilted or flexed position and the tool in a position in which it may serve as a flagstaff;

50 FIG. 3 is a side elevational view of modified motion transmitting means;

55 FIG. 4 is a fragmentary side elevational view of modified supporting means; and

60 FIG. 5 is a fragmentary axial section through a further connection wherein the device for shifting the motion transmitting means may be manipulated from the interior of the tent.

65 Referring first to FIG. 1, there is illustrated a portion of a skeleton structure or frame which may be utilized to support and to expand a canvas (not shown) in such a way that the canvas preferably resembles a cupola or dome. The skeleton structure comprises two or more arcuate tent poles or ribs 10 (only one shown) preferably consisting of elastically deformable material and having their lower end portions secured in or to the ground in a manner not forming part of the present invention. Each tent pole 10 may consist of wood, metal, plastic or another suitable elastically deformable material so that it can be flexed in response to movement of its upper

end portion 10a in a downward direction, as viewed in FIG. 1.

The skeleton structure further comprises a novel connection for the upper end portions 10a of the tent poles, and this connection includes a rigid metallic main supporting member here shown in the form of a hollow substantially frustoconical body 1 having an annular central portion or top portion 1a and a fulcrum or skirt 1b, the latter diverging downwardly and outwardly from the central portion 1a. The skirt 1b is provided with a series of suitably distributed apertures or slots 9 each of which may receive one of the poles 10 in such a way that the end portion 10a extends beyond the respective aperture 9 and into the interior of the hollow supporting member 1. When the supporting member 1 moves up or down, as indicated by a double-headed arrow 1c, the poles 10 will be tilted about the lower or upper surfaces bounding the respective apertures 9 whereby the poles may be flexed to a desired degree so as to bring about requisite stretching of the canvas which surrounds the skeleton structure.

The tensioning means for the poles 10 comprise a substantially cup-shaped motion transmitting member or gripper 8 which is located in the interior of the skirt 1b and engages the end portions 10a. This member 8 is rigidly secured to the lower end portion of a vertically extending spindle 2 whose threads 6 mesh with internal threads provided in the spindle nut 3. The latter is coaxially and rotatably mounted in the central portion 1a of the supporting member 1 which central portion holds the nut 3 against axial movement. Thus, when the nut 3 is rotated by means of a suitable tool 4, and when the end portions 10a hold the spindle 2 against rotation with reference to the supporting member 1, the spindle will move axially up or down (arrow 1c), depending on the direction in which the nut 3 rotates, and will thereby cause the poles 10 to tilt with reference to the skirt 1b. It is clear that the threads 6 may but need not extend all the way between the ends of the spindle 2.

The lower edge portion of the cupped motion transmitting member 8 is provided with a series of suitably distributed relatively shallow recesses or notches 11 each of which may receive one end portion 10a to thus prevent rotation of the member 8 in response to rotation of the nut 3. The notches 11 also insure that the end portions 10a cannot swing laterally, i.e., that the end portions extend substantially radially with reference to the vertical axis of the supporting member 1. All of the notches 11 need not be of the same depth so that, when the spindle 2 moves downwardly, as viewed in FIG. 1, certain poles 10 will be flexed earlier than the remaining poles. This is important in certain types of tents wherein the skeleton structure comprises two or more sets of poles and wherein each set of poles must be tilted or flexed to a different degree. For example, the shallower recesses 111 of the member 108 shown in FIG. 3 will receive the end portions of main tent poles whereas the deeper recesses 111a receive the end portions of auxiliary poles which must be flexed to a lesser degree than the main poles. The poles whose end portions 10a extend into shallower recesses 111 may be tilted to such a degree that each thereof extends at right angles to the axis of the spindle 2. Furthermore, the supporting member 1 may carry two or more motion transmitting members each of which can tilt one or more poles.

The tool 4 resembles a wrench and is provided with a non-circular cutout or opening 4a (see FIG. 2) which may receive a complementary portion 3a of the spindle nut 3 so that the nut must rotate when the tool is applied in a manner as shown in FIG. 1 and is turned about the vertical axis of the supporting member 1. In accordance with an optional but highly advantageous feature of my invention, the top portion of the spindle 2 may be provided with a diametral slot 2a which can receive a flat tongue or lug 5 at the front end of the tool 4 so

that, when the lug 5 extends into the slot 2a, the tool 4 extends vertically upwardly and its rear end portion 7 may carry a flag or banner. Another advantage of the tool 4 is that, when attached to the spindle 2, it is always ready and close at hand so that the person in charge need not look for the tool when he or she desires to take the skeleton structure apart for transport to another camping site.

FIG. 2 illustrates the skeleton structure in fully assembled condition with the tool 4 extending vertically upwardly so that its rear end portion 7 may carry a flag or the like, not shown. It will be seen that the tent pole 10 of FIG. 2 is tilted in a clockwise direction with reference to the position of FIG. 1 so that the canvas which is engaged by a median portion of the pole 10 is caused to assume a desired shape, for example, the shape of a cupola or dome.

It is clear that the connection shown in FIGS. 1 and 2 is equally useful for assembling a skeleton frame which comprises straight tent poles and that the connection may be used in skeleton structures which comprise only two tent poles or three or more poles. Also, the poles may be hollow or solid and each thereof may have a circular, oval or polygonal cross section.

In erecting the skeleton structure, the person in charge secures the lower end portions of the poles 10 to the ground and to the lower edge of the canvas. The upper end portions 10a are introduced through the apertures 9 and into the respective notches 11 so that the motion transmitting member 8 is held against rotation and simultaneously prevents rotation of the spindle 2. At the same time, the poles 10 hold the skirt 1b against rotation about the axis of the supporting member 1. The operator then rotates the nut 3 in a sense to move the spindle 2 downwardly, as viewed in FIG. 1, whereby the motion transmitting member 8 moves away from the central portion 1a and tilts the poles 10 with reference to the skirt 1b. It will be seen that the skirt 1b constitutes a fulcrum or pivot for the poles 10 and cooperates with the member 8 to flex the poles with simultaneous stretching of the canvas. The end portions 10a may be withdrawn from the slots 9 as soon as the nut 3 is rotated to move the member 8 back to the axial position of FIG. 1.

The motion transmitting member 8 may be reciprocated by resorting to devices other than the spindle 2 and nut 3. For example, one can resort to a lever, to an eccentric or the like.

FIG. 4 illustrates a further modification according to which the skirt 201b of a supporting member 201 is connected with the central portion 201b by means of spokes 201d and wherein the area of each aperture 209 may be varied by an adjusting member 201e which is adjustably secured to the skirt 201b by bolts 201f extending through elongated slots 201g. The arrangement of FIG. 4 brings about similar advantages as the arrangement shown in FIG. 3, i.e., the initial position of the poles 10 may be varied so that certain poles will be flexed to a different extent than the remaining poles. The adjusting members 201e may be used with equal advantage on the motion transmitting member 8 or 108 to change the depth of the notches 11, 111 and/or 111a. Also, such adjusting members may be attached to the central portion 201a.

Finally, it is equally possible to construct the nut in such a way that it may be rotated from the underside of the central portion 1a, i.e., from the interior of the tent. This is of particular advantage when the tent is high. All that is necessary is to provide the nut 303, see FIG. 5, with a non-circular portion 303a (corresponding to the portion 3a) which is located at a level below the central portion 1a of the supporting member 1.

A very important advantage of all embodiments of my improved skeleton structure is that the upper end portions 10a of the poles 10 need not be connected to each other and that such upper end portions may be inserted

into the respective apertures **9** one after the other, rather than in pairs. Also, all of the poles can be tilted and flexed or unflexed in a simultaneous operation and in response to the application of a relatively small force, especially if the tool **4** is rather long.

Without further analysis, the foregoing will so fully reveal the gist of the present invention that others can, by applying current knowledge, readily adapt it for various applications without omitting features which fairly constitute essential characteristics of the generic and specific aspects of my contribution to the art and, therefore, such adaptations should and are intended to be comprehended within the meaning and range of equivalence of the following claims.

What is claimed as new and desired to be protected by Letters Patent is:

1. In a tent, particularly in a dome-shaped tent, a skeleton structure comprising at least two poles each having an upper end portion; a hollow substantially frustoc conical supporting member having a substantially vertical axis and including a smaller-diameter central portion at the upper end thereof and an outwardly and downwardly diverging skirt provided with a plurality of apertures receiving said poles so that the upper end portions of the poles extend into the interior of said skirt; and tensioning means for tilting said poles with reference to said skirt, said tensioning means comprising a cupped motion transmitting member having an edge portion provided with recesses for the upper end portions of said poles, a spindle nut rotatably mounted in said central portion, and a spindle meshing with said nut and fixed to said motion transmitting member so that, when the nut is rotated with reference to said supporting member, the motion transmitting member moves axially and tilts the poles with reference to said skirt.

2. A skeleton structure as set forth in claim **1**, wherein said recesses include recesses of greater and lesser depth.

3. In a tent, particularly in a dome-shaped tent, a skeleton structure comprising at least two tent poles having lower end portions which may be attached to the ground and upper end portions; hollow supporting means having a substantially vertical axis and including fulcrum means provided with apertures removably receiving said poles so that the upper end portion of each pole extends into the interior of said supporting means; tensioning means mounted on said supporting means and including motion transmitting means comprising a cupped member having a lower edge portion provided with recesses receiving the upper end portions of said poles from

above and means for shifting said motion transmitting means in the axial direction of said supporting means whereby the poles are tilted with reference to said fulcrum means when the motion transmitting means moves downwardly.

4. A skeleton structure as set forth in claim **3**, further comprising means for adjusting the areas of said apertures to thereby change the initial position of said upper end portions with reference to the axis of said supporting means.

5. A skeleton structure as set forth in claim **3**, wherein said recesses include recesses of lesser and greater depth so that the inclination of an upper end portion which extends into a shallower recess is different from the inclination of an upper end portion which extends into a deeper recess.

6. In a tent, particularly in a dome-shaped tent, a skeleton structure comprising at least two tent poles having lower end portions which may be attached to the ground and upper end portions; hollow supporting means having a substantially vertical axis and including a central portion, an annular skirt located at a level below said central portion, and spokes connecting said central portion with said skirt, said spokes defining between themselves a plurality of apertures removably receiving said poles so that the upper end portion of each pole extends into the interior of said supporting means; and tensioning means mounted on said central portion and including motion transmitting means engaging said end portions from above and means for shifting said motion transmitting means in the axial direction of said supporting means whereby the poles are tilted with reference to said skirt when the motion transmitting means moves downwardly and away from said central portion.
